UNITED STATES PATENT OFFICE.

CLARENCE WOOLLEY, OF WAUKEE, IOWA.

AUTOMATIC HIGH-PRESSURE ACETYLENE-GAS GENERATOR.

No. 926,632.

Specification of Letters Patent.

Patented June 29, 1909.

Application filed September 24, 1908. Serial No. 454,940.

To all whom it may concern:

Be it known that I, CLARENCE WOOLLEY, a citizen of the United States of America, and resident of Waukeen, Dallas county, Iowa, have invented a new and useful Automatic High-Pressure Acetylene-Gas Generator, of which the following is a specification.

The object of this invention is to provide an improved construction for acetylene gas generators.

My invention consists in the construction, arrangement and combination of elements hereinafter set forth, pointed out in my claim and illustrated by the accompanying drawing, in which—

Figure 1 is a plan and Fig. 2 a side elevation of the complete device. Fig. 3 is a vertical section on the indicated line 3—3 of Fig. 1 and Fig. 4 is a vertical section on the indicated line 4—4 of Fig. 1.

In the construction of the device as shown the numeral 10 designates a casing, preferably of rectangular shape and made of sheet metal, and imperforate except as hereinafter described. The casing 10 preferably is of a height somewhat greater than its width and a partition 11 is mounted vertically and transversely thereof and is sealed at its margins to the front and rear walls, the top and bottom of the casing. A partition 12 is mounted vertically within the casing and transversely of one portion thereof, and said partition has its margins sealed to one side wall, the top and bottom of the casing and to the partition 11. Thus three compartments or chambers 13, 14, 15 are formed within the casing, the first having a capacity approximately equal to the other two combined. The chamber 13 is for the storage of gas, the chamber 14 is for the generating of gas and may be termed a carbide chamber, and the chamber 15 forms a water tank. Pipe 16 and valve 16^a are provided in the upper end portion of the partition 11 to afford communication between the gas chamber and the carbide chamber. A basket 17 is suspended in the upper portion of the carbide chamber and preferably is of hopper form and provided with a mesh bottom 18. An opening 50 is formed in the top of the casing 10 communicating with the basket 17 and said opening normally is closed by a plug 19. The opening, closable by the plug 19, is employed to supply carbide to the basket 17 or to admit water to cleanse the basket and the carbide chamber 14. A drainage port is formed in

the bottom of the casing communicating with the carbide chamber and normally is closed by a plug 20. The drainage port is employed to drain ashes and water from the carbide chamber.

A water pipe 21, preferably of minute cross-section, is mounted through the top of the casing 10 in two places and is sealed thereto. One end portion of the pipe 21 extends nearly to the bottom of the water tank while the opposite end portion of said pipe extends nearly to the bottom of the carbide basket 17. A check valve 22 is mounted in the pipe 21 and prevents reverse flow from the carbide chamber to the water tank. An opening is formed in the top of the casing and communicates with the water tank and said opening normally is closed by a plug 23. The opening, closable by the plug 23, is employed to supply water to the tank 15. An air pipe 24, controlled by a valve 25, is mounted through and sealed to the top of the casing and extends into the water tank 15. The air pipe leads from a source of pressure (not shown) such as an air pump on an automobile, or locomotive. A pressure indicator 26 is mounted on the top of the casing 10 and communicates with the interior of the water tank 15. A pressure indicator 27 is mounted on the top of the casing 10 and communicates with the interior of the gas chamber 13. A discharge pipe 28, controlled by a valve 29, leads from the interior of and is sealed to the gas chamber 13. One or more sections of hose (not shown) may be attached to the discharge pipe 28 and lead to lamps or tire valves, for the purpose of supplying illuminating gas to the lamps or filling medium to the tires.

Water, in successive small quantities, is forced through the pipe 21 into the carbide by air pressure created in the water tank through the pipe 24. The water acts on the carbide for the production of gas which fills the carbide chamber and gas chamber and reacts on the air pressure, and reverses the flow of water to the chamber 15. Repeated applications of air to the water tank will increase the supply of gas to the desired degree as shown by the indicator 27, without risking damage to the machine by excessive pressure. The gas generated by the latest flow of water upon the carbide creates a pressure in the chambers 13, 14 superior to the air pressure in the chamber 15 and, therefore, gas flows rearwardly through the pipe 21 and

bubbles through the water and mixes with the air in said chamber 15, thus equalizing the pressure in said chambers. Then, as gas is used from the chamber 13 the pressure in the latter chamber is reduced. Such reduction of pressure in the chamber 13 is responded to by discharge of more water on the carbid, which results in generating more gas and further re-acting and equalizing of pressures until the water is exhausted. The supply of water is replenished, after closing the valve 22, by removing the plug 23 and filling the chamber 15 to the desired extent, and such removal of the plug and introduction of water discharges the mixed air and gas from said chamber 15 through the filling port. Then the plug 23 is replaced and the pressure in the chamber 15 is raised to operative degree by pumping air through the pipe 24. The valve 22 is then opened and the operation proceeds as before. A drainage port is formed in the bottom of the casing communicating with the water tank and normally is closed by a plug 20^a.

25 A quantity of gas can be retained in the storage chamber 13 at high pressure, to be used automatically as desired by closing the valve 16^a, and the supply of gas is automatically maintained when said valve is open by maintaining a desired pressure in the water tank as above described. The valve 16^a is closed during the operation of re-charging the carbid chamber.

I claim as my invention—

35 An acetylene gas generator, comprising a casing having a storage chamber, a carbid

chamber and a water tank side by side therein, means for supplying water to and drawing the same from said tank, a pipe on the top of said casing and extending within 40 the water tank and carbid chamber, one end of said pipe extending nearly to the bottom of the water tank, a manually operated, normally open valve in said pipe, said pipe adapted to convey water in one direction to 45 the carbid chamber and gas in the opposite direction to the water tank when said valve is open, a carbid basket suspended in and spaced from the bottom of the carbid chamber, one end portion of said pipe extending 50 within and nearly to the bottom of said basket, a closable port in the top of the carbid chamber whereby carbid can be supplied to said basket, a closable drainage port in the bottom of the carbid chamber, a pipe within 55 and beneath the top of said casing and adapted for gas communication between the carbid chamber and storage chamber, a manually operated valve in said pipe, a valve-controlled service pipe leading from 60 the storage chamber, a pressure pipe entering the water tank, a valve in said pressure pipe, and pressure indicators in the top of the casing and communicating with the water tank and storage chamber.

Signed by me at Des Moines, Iowa, this twenty fifth day of August, 1908.

CLARENCE WOOLLEY.
